UNITED STATES PATENT OFFICE.

EMERSON E. WINSTEAD, OF DRESDEN, TENNESSEE.

HAME.

SPECIFICATION forming part of Letters Patent No. 296,497, dated April 8, 1884.

Application filed November 10, 1883. (No model.)

To all whom it may concern:

Be it known that I, EMERSON E. WINSTEAD, a citizen of the United States, and a resident of Dresden, in the county of Weakley and State 5 of Tennessee have invented certain new and useful Improvements in Hames; and I do hereby declare that the following is a full, clear, and exact description of the invention, which will enable others skilled in the art to 10 to which it appertains to make and use the same, reference being had to the accompanying drawings, which form a part of this specification, and in which—

Figure 1 is a perspective view of my improved hame. Fig. 2 is a front view of part 15 of the same, and Fig. 3 is a side view of the lock-fastening for the trace-hook.

Similar letters of reference indicate corresponding parts in all the figures.

20 My invention has relation to that class of hames in which the hame-strap and the trace-hook may be adjusted to suit different-sized collars; and it consists in the improved construction and combination of parts of the ad- 25 justable lock-fastening for the trace-hook, as hereinafter more fully described and claimed.

In the accompanying drawings, the letter A indicates the hame, having at its upper end 30 a series of bails, B, in which the hame-strap may be inserted, according to the size of collar which the hame is intended to fit. At the lower end the hame is provided with a bail, C, through which the fastening-strap passes, or it may have any othersuitable fasten- 35 ing. A plate, D, is secured upon the front side of the hame, and is provided at equal distances with a number of parallel projecting steps or lugs, E, which have eyes or perforations F near their forward ends, through

40 which perforations a lock bolt or rod, G, is removably inserted, having a head or knob, H, at its upper end, which prevents it from passing through the perforations, and provided with a spring-catch, H', below the head, 45 adapted to bear with its free projecting end against the under side of the uppermost of the series of perforated steps or projections E, through which the bolt is inserted.

I is the trace-hook, which is flat and of the same width as the distance between two of the 50 steps, and has a transverse eye or aperture, J, at its inner end, through which the lock-bolt is inserted, thus hinging the hook upon the hame between two adjacent steps or lugs E. In this manner it will be seen that by 55 pressing the free end of the spring-catch against bolt G and withdrawing the bolt, removing the hook from between its two steps, inserting it between two other steps, and again inserting the lock-bolt, the hook may be ad- 60 justed to bring the line of draft to its proper point, and the hook fitting snugly between two adjacent steps, the said steps will bear all lateral draft upon the hook, preventing it from bending the lock-bolt, which might easily 65 happen if the hook were not supported upon both sides.

I am aware that hames have been construct- 70 ed before with laterally-projecting steps, or a plate having laterally-projecting steps, in com- 75 bination with an adjustable trace-hook adapt- ed to fit between the steps, and held in place by a rod inserted through the steps and through a groove or an eye in the body of the hook; neither do I claim such construction, broadly; 75 but

What I claim as my improvement, and desire to secure by Letters Patent of the United States, is—

The combination, with the hame having 80 plate D, provided with the projecting perforated steps E, and trace-hook I, having eye J, of the removable lock-bolt G, constructed with the spring-catch H' below its head H, whereby the bolt is locked, removably, between the up- 85 per and under side of the topmost step or projection, as shown and specified.

In testimony that I claim the foregoing as my own I have hereunto affixed my signature in presence of two witnesses.

EMERSON E. WINSTEAD.
